DESIGN FOR A TRAY OR THE LIKE

Alfred F. Reilly, North Attleboro, Mass., assignor
to Evans Case Company, North Attleboro,
Mass., a corporation of Massachusetts

Application March 5, 1934, Serial No. 50,942

Term of patent 7 years

To all whom it may concern:

Be it known that I, ALFRED F. REILLY, a citizen of the United States, residing at North Attleboro, county of Bristol, and State of Massachusetts, have invented the new, original, and ornamental Designs for Trays or the like, of which the following is a specification, reference being had to the accompanying drawing, forming a part hereof.

The drawing is a perspective view of a tray or the like showing my design. The number of the elements marked A may be varied as the relative length and breadth of the base marked B is varied.

I claim:

The ornamental design for a tray or the like, substantially as shown and described.

ALFRED F. REILLY.
